UNITED STATES PATENT OFFICE.

JOHN KEENAN, OF CHICAGO, ILLINOIS, ASSIGNOR, BY MESNE ASSIGNMENTS, TO INTER-
TYPE CORPORATION, A CORPORATION OF NEW YORK.

SLUG-MOLD.

1,210,077.

Specification of Letters Patent. Patented Dec. 26, 1916.

Application filed April 22, 1912. Serial No. 692,432.

To all whom it may concern:

Be it known that I, JOHN KEENAN, a citizen of the United States, and a resident of Chicago, county of Cook and State of Illinois, have invented certain new and useful Improvements in Slug-Molds, of which the following is a specification.

My invention relates to improvements in line casting machines and has particular reference to improvements in slug molds for such machines.

The object of my invention is to provide a mold for slug casting machines which shall facilitate and cheapen the production of skeleton slugs.

A further object of my invention is to provide a mold by means of which skeleton slugs of different lengths can be produced without the necessity of using liners of special cross section.

A further object of my invention is to provide a slug mold by means of which a skeleton slug having a thin portion in its body and a wide face can be cast of any desired length by the use of the usual parallel thickness liners.

My invention resides in a slug mold provided in one face with a series of recesses, openings or notches separated by partitions, and by means of which the molten metal is fed from the body of the mold to the wide face.

My invention consists further in a slug mold adapted to make skeleton slugs of different specified lengths and having grooves in one face adapted to feed the metal to the face of the slug.

My invention will be more readily understood by reference to the accompanying drawings forming a part of this specification, and in which—

Figure 1 is a front elevation of a mold of the type commonly employed in connection with linotype slug casting machines and made in accordance with my invention; Fig. 2 is a vertical section of the mold upon the line 2—2 of Fig. 1 shown in connection with a matrix in casting position in front of the mold; Fig. 3 is a perspective view of a skeleton slug, such as would be produced in or by the mold illustrated in Fig. 1; Figs. 4 and 5 are detail transverse sections of the slug upon the lines 4—4 and 5—5 respectively of Fig. 3.

It should be understood that skeleton slugs have been made heretofore on linotype machines, but the use of the molds in making these slugs has necessitated the employment of special liners, when it is desired to make slugs of any length shorter than the whole length of the mold. These special liners have been required for the purpose of closing the front of the mold to prevent the metal from flowing longitudinally along the face of the mold in that part of the mold which produces the wide face of the slug. When it is understood that skeleton slugs of many widths of faces are used and that it is necessary to provide a complete complement of liners so that skeleton slugs of each width of face and of all the different lengths can be produced, it will be understood that the equipment necessary for producing these slugs requires the investment of a large amount of capital in special liners. Each linotype machine carries as its standard equipment a complete set of liners which are substantially parallel in thickness and are used for making the standard solid linotype slugs of the different lengths required and one of the particular objects of my invention is to provide a mold of such form that skeleton slugs can be produced thereby of any desired length with the use of the standard parallel thickness liners which is the standard equipment of all linotype machines. "Linotype," as used herein, will be understood to refer to any of the slug casting machines and is not limited to the machines known as the linotype machines.

In said drawings A indicates a modified standard linotype mold similar to the standard mold which is usually employed upon linotype machines. It consists of a base member 2 and a cap member 3, separated from each other by a space 4 and held in position one upon the other by any suitable means such, for instance, as screws 5. The cap is held above the base by means of a permanent liner or spacer 6 at one end and a changeable liner or spacer 7 at the other end. These spacers are clamped between the adjacent opposed faces of the base and cap and are held in position by the clamping of the cap upon the base and are adapted to space the two parts of the mold apart a sufficient distance to provide a space in which

a slug can be formed having a thin portion in the body thereof. To adapt the mold to produce slugs which have faces that are wider than the thickness of the thin portion 5 of the body I provide the cap, in its outer face, with a series of recesses or openings 8 separated from each other by a series of thin partitions 9. These recesses or openings open through the face 10 of the mold and 10 through the bottom 11 of the cap; that is, they form continuations of the slug space 4 and extend the front face of the mold space upward a sufficient distance to coöperate with the letter forming space 13 provided in 15 the matrices 14 with which the mold is adapted to be employed to form a skeleton slug. A certain number of the spaces 8 extend through to the rear face of the mold and thereby the thin portion of the body of 20 the slug is provided with ribs 15, which together with the thin portion of the body of the slug 16 formed in the slug space 4 make the complete skeleton slug, as illustrated in Fig. 3. The recesses 8 and partitions 9 form 25 what may properly be termed a longitudinal groove along the front edge of the cap which is divided or closed at intervals by the partitions 9.

It is desirable in making slugs to be able to produce slugs of different lengths and to be able to vary these lengths within certain definite dimensions. To make a slug, in the mold which I have provided, of a length which is shorter than the complete length of the mold, it is simply necessary to select the liner 7 of a suitable length so that its inner end will be properly spaced from the opposite permanent liner that a slug space of the required length is formed between the opposed ends of the two liners, and I arrange the partitions 9 in such relation to the lengths of slugs which it is desired that the mold shall produce that the inner end 17 of the adjacent liner 7 shall coincide with one of the partitions 9. Consequently, when the liner is in position between the base and cap and its inner end 17 coincides with one of the partitions 9 the molten metal, of which the slug is formed, is effectually prevented from flowing along the face of the mold as the liner and the partition 9 with which the end coincides form a complete partition or dam at that end of the mold. The combined width of one of the spaces 8 and the adjacent partition 9 can be made in any desirable dimension, but I preferably make this dimension equal to a printer's "m" so that the resultant variation in the length of the slugs is in "m" lengths. It will be understood, of course, if it is desired to produce any other length of slug which might vary by half "m" or other dimensions it is only necessary, in manufacturing the mold, to place one of the partitions in the desired position.

to coöperate with the necessary length of liner to produce the length of slug desired.

As many modifications of my invention will readily suggest themselves to those who are skilled in the art, I do not confine or limit my invention to the specific constructions herein shown and described.

I claim:

1. A slug mold having opposed sides spaced apart to form a slug space for casting a slug having recesses in one side to produce a thin portion in the slug body, recesses in one side of the mold extending partially through the mold transversely and opening through the face of the mold to form a slug having a face wider than the thickness of said slug space, and partitions extending to the face of the mold separating said recesses. 011

2. A slug mold having opposed sides spaced apart to provide a slug-forming space for casting a slug having recesses in one side to produce a thin portion in the slug body, there being spaced recesses in one side extending partially through the mold transversely and opening through the forward face of the mold to form a slug having an effective face wider than the thickness of said thin portion of the slug body, said spaced recesses being separated by relatively thin partitions, the edges of which are flush with the adjacent surfaces of the mold.

3. A slug mold having opposed sides and liners spacing said sides apart to form a slug space for casting a slug having recesses in one side to produce a thin portion in the slug body, substantially uniformly and relatively wide spaced recesses in one side and extending partially through the mold transversely, the majority thereof opening into the slug space and through the front face only of the mold to form a slug having a face wider than the thickness of said thin portion of the slug body, and relatively thin partitions between said recesses having their edges flush with the adjacent surfaces of the mold and being substantially uniformly spaced apart. 96 06 08

4. A slug mold having opposed substantially parallel sides spaced apart to form a relatively thin slug space for casting a slug having recesses in one side to produce a thin portion in the slug body, said sides being held in such spaced relation by liners arranged between the ends of said sides, one of said sides being provided with uniformly spaced recesses at its front edge extending partially through the mold transversely, said recesses opening into the slug space and through the front face of the mold and adapting the mold to form a slug having a face wider than the thickness of said thin portion of the body of the slug, certain of said spaces extending substantially through 99

the body of the mold to the rear face thereof to form parallel ribs on one side of said thin portion of the slug body and partitions extending to the front face of the mold and spacing the recesses apart.

5. A slug mold having opposed substantially parallel sides spaced apart to cast a slug recessed in one side of its body to form a thin portion in the body of the slug, in combination with liners arranged between said sides and holding them in spaced relation to form a slug space, one of said sides being provided with substantially uniformly spaced recesses opening into the slug space and the major portion thereof opening through the front face only of the mold adapting the mold to produce a slug having a relatively thin portion in its body and a relatively wide face, and thin partitions separating said spaces and having their edges flush with the adjacent faces of the mold side.

6. A slug mold having opposed sides in combination with liners interposed between said sides and holding them in spaced relation, one of said sides having longitudinally spaced grooves adapting the mold to form a slug having a thin portion in its body and a face wider than said thin portion in the body of the slug, uniformly spaced transversely extending partitions dividing said grooves and having their edges flush with the adjacent faces of said mold side and adapted to coöperate with the inner end of a liner to effectually prevent the flow of metal along said groove beyond the end of the slug being cast.

7. A slotted slug mold having a series of recesses spaced along one of its front-face edges, said recesses extending partially through the body of the mold a uniformly short distance and opening into the slug space and adapting the mold to form a slug having a relatively thin portion in its body and a face wider than said thin portion, the partitions separating said recesses being relatively thin and having their edges flush with the adjacent surfaces of the mold.

8. A slotted slug mold adapted to cast a slug recessed in one side to form a thin portion in the body thereof and having a series of recesses spaced along one of its front face edges and extending partially through the mold transversely, partitions between the recesses having two free edges, one being flush with the surface adapted to form the upper surface of the thin portion of the slug body and the other thereof being coincident with the front face of the mold.

60 9. A slotted slug mold adapted to form skeleton slugs of different lengths and having thin portions in the bodies thereof, comprising opposed sides and liners spacing said sides apart, one of said sides being provided along its front edge with substantially uni-

formly spaced, relatively wide notches extending partially through the mold transversely and separated by substantially uniformly spaced, transversely extending, relatively thin partitions, each said partition being adapted to coöperate with the inner end of the liner to form one end of a slug and to prevent the flow of slug-forming metal beyond the end of the slug being cast.

10. A slotted mold formed in its front surface with transverse cavities communicating with the mold slot and extending therefrom substantially in a perpendicular plane, a portion of said cavities extending partially and others wholly through the mold transversely, so as to produce a slug having a thin portion in its body and relatively wider portions on its edge.

11. A slotted mold formed in its front surface with transverse cavities communicating with the mold slot and extending therefrom substantially in a perpendicular plane, said cavities being arranged in sets of different lengths so as to produce a slug with a relatively thin portion in its body, relatively wider character bearing portions on its edge, and having on one side of the thin portion of its body relatively long ribs to facilitate assembling the slugs in column and relatively shorter supporting projections for the character bearing portions.

12. A slug mold having opposed sides, in combination with liners interposed between said sides and holding them in spaced relation to cast a slug recessed in one side to produce a thin portion in the body thereof, one of said sides having a series of tapered recesses along its front edge, the majority whereof open into the slug space and through the face only of the mold, partitions separating said recesses, said partitions having their edges flush with the adjacent face of the mold side and adapted to coöperate with the inner end of a liner to effectually prevent the flow of metal along the face of the mold beyond the end of the slug.

13. A slug mold having opposed sides in combination with liners interposed between said sides and holding them in spaced relation to cast a slug recessed in one side to produce a thin portion in the body thereof, one of said sides having spaced recesses along its forward edge to form a slug having a face wider than the thin portion of the body thereof, transversely extending partitions arranged between the recesses, each thereof having its edge flush with the adjacent face of said mold side and adapted to coöperate with the inner end of the adjacent liner to effectually prevent the flow of metal beyond the end of the slug being cast.

14. A slug mold having opposite sides spaced apart to provide a slug forming

- space for casting a slug having a thin portion in the body thereof, one side of the mold being provided with a series of recesses extending inwardly from the forward 5 face thereof, the major portion of said recesses extending but a short distance into the mold side and serving to form on a slug formed in the mold character supporting projections wider than the thin portion 10 of the body of the slug, and the remaining recesses extending through the mold side to the rear face thereof and being adapted to form spacing ribs on the thin portion of the body of a slug cast in the mold.
15. 15. A mold for coöperation with a line of character forming matrices to form a skeleton character bearing slug, said mold having a slug body space which is relatively thin to form thin portions in the 20 body of the slug and being provided with a series of spaced shallow recesses extending transversely therefrom and opening through the face of the mold to provide a wide character bearing face to receive and 25 support the characters formed in said matrices.
16. A mold for coöperation with a line of character forming matrices to form a slug comprising a cap member and a base 30 member, liners holding said members spaced apart to form a slug space which is relatively thin to form a thin portion in the body of the slug, one of said members being provided with a series of spaced 35 recesses continuing the slug space transversely to provide a wide face on the slug formed in the mold, partitions separating said recesses, and the inner ends of said liners being adapted to coöperate with certain 40 of said partitions and with the line of matrices to prevent the flow of metal beyond the end of the line of matrices.
17. In a machine of the linotype class, a slug mold having a main slot for casting 45 a relatively thin portion in the body of the slug, transverse grooves for casting substantially parallel ribs on one side of the thin portion of the body to facilitate clamping the slugs in column, and intermediate shorter grooves for casting character supporting projections. 50
18. In a machine of the linotype class, a slug mold having a slot for casting a relatively thin portion in the slug body, transverse grooves for casting substantially parallel ribs on the thin portion of the slug body, and intermediate relatively shorter transverse grooves extending only partially through the mold for casting character supporting projections. 55
19. In a machine of the linotype class, a slug mold having a slot for casting a relatively thin portion in the slug body, transverse grooves for casting substantially parallel ribs on the thin portion of the slug 60 body, and intermediate shorter grooves extending from the matrix face of the mold partially through the mold transversely and communicating with said slot, partitions separating the latter grooves, the edges of the partitions being flush with the matrix face of the mold and with the adjacent wall of the mold defining said slot. 65
20. In a machine of the linotype class, a slug mold having a slot for casting a relatively thin portion in the slug body, transverse grooves communicating with said slot for casting substantially parallel ribs on the thin portion of the body of the slug, and intermediate shorter grooves extending 70 from the matrix face of the mold partially through the latter and communicating with said slot for casting character supporting projections on the thin portion of the slug body, partitions separating the latter 75 grooves and having their edges flush with the matrix face of the mold and with the adjacent face of the mold defining said slot, and liners for defining the length of said slot, said liners coöoperating with the flush 80 edges of said partitions. 85
- In testimony whereof, I have hereunto set my hand, this 20th day of April, 1912, in the presence of two subscribing witnesses.
